UNITED STATES PATENT OFFICE.

RENATUS JOSEF OTT, OF SAALFELD, GERMANY.

HAIR-UNDULATING APPARATUS.

Application filed February 16, 1924. Serial No. 693,365.

To all whom it may concern:

Be it known that I, RENATUS JOSEF OTT, a citizen of the Republic of Germany, residing at Saalfeld, Germany, have invented 5 certain new and useful Improvements in Hair-Undulating Apparatus, of which the following is a specification.

This invention relates to an apparatus for waving the hair. The apparatus of this 10 kind are based on the principle that the hair is gripped between tongs consisting of a lower jaw of undulated sheet metal serving as support for the hair and of a narrow transverse upper jaw of undulated sheet 15 metal movable with regard to the lower jaw. The hair spread in this manner is held by two fork-shaped side arms so that at first a simple wave is produced from which the so-called Marcel wave is obtained by displacement of the two parts of the apparatus. 20 The hair is however submitted to strong tensile stress as the first curve of the hair extending transversely to the rounding of the tongs must be further extended in forward 25 and backward direction so that the hair in the tongs is torn and pulled in opposite directions wherefrom results a very injurious effect. A further inconvenience consists in that at the displacement of the parts of the 30 tongs the hair does frequently not move with these parts as it cannot afford the necessary displacement so that the undulation becomes irregular and of bad appearance.

This invention has for its object to obviate 35 these inconveniences by creating a waving apparatus in which the hair is arranged at different heights above the supporting jaws, the layers of hair being displaced with regard to one another with the aid of a set-off 40 frame in such a manner that no injurious pull is executed on the hair.

The invention will be best understood from a consideration of the following detailed description taken in connection with 45 the accompanying drawings forming part of this specification, with the understanding that while in the drawings one embodiment of the invention is disclosed, the invention is not confined to any strict conformity with 50 the showing of the drawings, but may be embodied in any manner which does not make a material departure from the salient features of the invention.

In the drawing:

55 Figs. 1 and 2 show the waving apparatus in side elevation in different positions.

Fig. 3 is a plan view of the apparatus, and Fig. 4 is an end view of the same viewed from the handle.

The waving apparatus consists of a longitudinal supporting frame *a* from which a rod *a*¹ with a handle *a*² projects. On this longitudinal frame *a* a movable frame is mounted which is adapted to be oscillated in forward and backward directions and consists of two end parts made from wire and connected with one another by comb-shaped side stays. 60

Each end part of this movable frame consists of a wire bent to form an upper horizontal rod *c* which is connected at both ends by means of downwardly directed inclined rods *d* and *e* with lower horizontal rods *f* and *g* from the outer ends of which outwardly inclined side rods *h* and *i* extend in 70 upward direction.

The comb-shaped lateral stays *h* are hingedly mounted on the upper ends of said inclined side rods *h* and *i* of the front and rear end parts, so that a frame is formed 80 which at the middle of the rods *e*, *d* has small lugs *m* which project in the longitudinal direction of the frame and are designed to receive laterally projecting studs *n* of frame *a*. The end parts of the movable frame are thus securely held on the horizontal handle frame but free to oscillate around the studs *n*. On the horizontal top rods *c* the feet *o* of the trough-shaped hair support 85 *p* are loosely mounted.

The upper jaw *q* designed to be placed upon the support *p* is hingedly mounted by means of two feet *r* on the horizontal rod *c* at the handle end of the apparatus. This upper jaw *q* has a convex lower surface 90 curved in accordance with the curvature of the concave lower jaw or support *p* and a flat top surface. If this upper jaw is hollow as shown the free space in the same may be used for accommodating any convenient 95 source of heat. On each lower horizontal rod *f* and *g* supports *s*, *t* respectively are mounted by means of feet, and on each of the lower supports, an upper jaw *u* *v* respectively is hingedly mounted. 100

Clamps *w* serve to hold the upper jaws pressed on the corresponding supports.

The undulating apparatus is used in the following manner:

The handle *a*² of the apparatus is held 110 with the left hand so that the teeth of the comb-shaped side stays *h* are upwardly di-

rected. After the clamps *w* have been removed and the upper jaws *v*, *g*, *u* have been raised the strand of hair is placed, transversely to the longitudinal direction 5 of the apparatus, over one of the stays *k*, the supports *t*, *p*, *s* and the other side comb *k*, the movable frame being in the vertical position as shown in Fig. 4. The upper jaws *u*, *g* and *v* are laid down so that the 10 hair is pressed into the concave supports *s*, *p* and *t* and the clamps *w* are put on. The strand of hair is thus waved but merely transversely to the longitudinal direction of the apparatus.

15 The position of the three supports *s*, *p*, *t* is now altered by oscillating the set-off frame around the studs *n*, the hair being brought out of the straight direction so that the waves are laterally deflected and the undulation is made to extend obliquely from 20 one wave to the other. The change of position is carried out without pulling the hair as the distances between the several supports remain the same, the parts of the 25 strand of hair from one support to the other extending from above to below obliquely in a lateral direction.

Owing to the fact that the supports *s*, *p*, *t* are not arranged and moved in the same 30 horizontal plane but oscillate around the pivot points *n* for a uniform distance forward and backward the strand of hair is undulated in laterally curved waves without being submitted to any pulling stress.

35 The upper part of the undulating apparatus can not only be oscillated in forward direction as shown in Fig. 2 but also in backward direction so that the next following portion of the strand of hair could be undulated in a direction opposite to that in 40

which the preceding strand of hair has been undulated.

Heated iron rods, electric heating resistances or any other convenient heating medium could be mounted in the hollow upper 45 jaws *u*, *g*, *v*.

I claim:—

A hair undulating apparatus comprising in combination a horizontal frame, a handle at one end of this horizontal frame, a movable frame mounted in this horizontal frame so that it can be oscillated about the same in forward and backward directions, said movable frame consisting of two end frames of wire bent to form an upper horizontal rod above said horizontal handle frame, two downwardly directed outwardly inclined inner side rods, two lateral horizontal rods situated below said handle frame at about the same distance as the horizontal top round stands above said handle frame, and two upwardly extending outwardly inclined outer side rods, of two comb-shaped side stays hinged each on the top ends of the two outer side rods at one side of the movable frame, three hair supports having a concave surface mounted on the said three horizontal rods at the two ends of said movable frame, and three hollow upper jaws having a flat top surface and a convex lower surface, hingedly mounted at one end to the horizontal rods of the handle and of said movable frame.

In testimony whereof I affix my signature in presence of two witnesses.

RENAUTS JOSEF OTT.
